JACOB B. MOORE, OF NEW YORK, N. Y.

Letters Patent No. 75,446, dated March 10, 1868.

IMPROVED WINDOW-SHADE FIXTURES.

The Schedule referred to in these Letters Patent and making part of the same.

TO ALL WHOM IT MAY CONCERN:

Be it known that I, JACOB B. MOORE, of New York, in the county and State of New York, have invented a new and useful Improvement in Window-Shade Fixtures; and I do hereby declare that the following is a full, clear, and exact description thereof, which will enable others skilled in the art to make and use the same, reference being had to the accompanying drawing, forming part of this specification.

The figure represents a window to which my improvement has been attached.

My invention has for its object to furnish a simple, cheap, and effective window-shade fixture, which will not be liable to get out of order, and which will obviate the annoyance now so generally experienced from the ordinary shade-fixtures getting out of order; and it consists in the construction, combination, and arrangement of the various parts, as hereinafter more fully described.

A represents the window-casing, B is the roller to which the shade C is attached, and around which it is wound. From the ends of the roller B project rods D of smaller diameter than said roller B, to which rods the cords E are attached, by which the shade is supported, said cords being wound several times around the said rods, in the direction shown in the drawing. By this construction and arrangement, the roller B being suspended by the cords E, the tendency is for the roller B to roll down in the direction to unwind the cords E from the rods D, rolling the curtain C up around the said roller. But the shade being left free, the tendency of the shade C is to unwind or roll the roller B in the opposite direction. To establish an equilibrium between these two forces, a rod, F, or equivalent weight is placed in or attached to the lower part of the shade, which should be of such a weight as to exactly balance the said forces, so that the said shade may be placed at any part of the window without changing its position. If, now, the equilibrium be destroyed by raising the bar or rod F with the hand, the roller B will roll down upon the cords E, winding up the shade C; and if the equilibrium is destroyed by drawing the bar or rod F downward, the shade will be drawn down or unwound from the roller, so as to cover or shade a larger part of the window. In case the window-casing is sufficiently wide to allow the shade C to be unwound without lowering the roller so far as to uncover the upper part of the window, the upper ends of the cords E may be attached to hooks or other supports secured to the upper part of the casing. But in ordinary cases, (and this construction I prefer,) the cords E may be passed through eyes G, or around guide-pulleys to the central part of the window, at which point they descend, and to their lower or free ends should be attached a weighted tassel, H, of such a weight as to exactly balance the roller B and shade C. This enables the shade when fully rolled up, or when unrolled to any desired extent, to be raised or lowered to shade any desired part of the window, or to leave any desired part of the window uncovered. If desired, the cord E may be guided to the side of the window, and pass down along the side-casing, so as to leave the front of the window more unobstructed, and so that the tassel H or other balancing weight may hang at the side, instead of in front of said window.

I claim as new, and desire to secure by Letters Patent—

1. Rolling or unrolling the curtain automatically by means of the cord, and the small axes of the roller, substantially as described.
2. Creating an equilibrium between the roller of the window-shade and the lower rod F, through the medium of the suspended cord and small axes D, whereby the shade is rolled or unrolled, substantially as herein shown and described.
3. In combination with the shade suspended upon axis D and the lower rod F, I claim the weight H, whereby said shade is held at any desired point, substantially as described for the purpose specified.

The above specification of my invention signed by me, this 18th day of January, 1868.

JACOB B. MOORE.
